CLAIM

The ornamental design for a staple cartridge, as shown and described.

DESCRIPTION

FIG. 1 is a perspective view of a first embodiment of a staple cartridge, showing our new design without surface shading.

FIG. 2 is a top view thereof.

FIG. 3 is a bottom view thereof.

FIG. 4 is a right-side elevational view thereof.

FIG. 5 is a left-side elevational view thereof.

FIG. 6 is a front elevational view thereof.

FIG. 7 is a rear elevational view thereof.

FIG. 8 is a perspective view of the first embodiment of the staple cartridge, showing our new design with surface shading.

FIG. 9 is a top view thereof.

FIG. 10 is a bottom view thereof.

FIG. 11 is a right-side elevational view thereof.

FIG. 12 is a left-side elevational view thereof.

FIG. 13 is a front elevational view thereof.

FIG. 14 is a rear elevational view thereof.

FIG. 15 is a perspective view of a second embodiment of a staple cartridge, showing our new design without surface shading.

FIG. 16 is a top view thereof.

FIG. 17 is a bottom view thereof.

FIG. 18 is a right-side elevational view thereof.

FIG. 19 is a left-side elevational view thereof.

FIG. 20 is a front elevational view thereof.

FIG. 21 is a rear elevational view thereof.

FIG. 22 is a perspective view of the second embodiment of the staple cartridge, showing our new design with surface shading.

FIG. 23 is a top view thereof.

FIG. 24 is a bottom view thereof.

FIG. 25 is a right-side elevational view thereof.

FIG. 26 is a left-side elevational view thereof.

FIG. 27 is a front elevational view thereof; and,

FIG. 28 is a rear elevational view thereof.

The broken lines in the drawings illustrate portions of the staple cartridge and form no part of the claimed design.
